TIRE

Harold D. Fetty, Birmingham, Mich., and Frederick F. Vannan, Akron, Ohio, assignors to The Goodyear Tire & Rubber Company, Akron, Ohio

Original design application Mar. 10, 1969, Ser. No. 16,135, now Patent No. 219,090. Divided and this application Jan. 6, 1970, Ser. No. 20,778

Term of patent 14 years

Int. Cl. D12—14

U.S. Cl. D90—20

FIG. 1

FIG. 2

FIG. 1 is a fragmentary side elevational view of a tire showing our new design, it being understood that the portion shown is repeated throughout the circumference of the tire, the opposite side of the tire being substantially the same as the side shown.

FIG. 2 is a partial section through the tire taken on line 2—2 of FIG. 1.

The characteristic features of our design reside in the repetitive pattern in the shoulder portion of the tire.

This is a division of my co-pending application Ser. No. D.16,135 filed Mar. 10, 1969, now Design Patent No. 219,090.

We claim:

The ornamental design for a tire, substantially as shown and described.
